ELECTRIC SWIVEL CONNECTION

Filed Feb. 2, 1946

UNITED STATES PATENT OFFICE

2,459,118

ELECTRIC SWIVEL CONNECTION

Frank J. Rehm, Jr., Elmwood Park, Ill., assignor
to Sittler Manufacturing Corp., Chicago, Ill.,
a corporation of Illinois

Application February 2, 1946, Serial No. 645,023

9. Claims. (Cl. 173—324)

1

This invention relates to improvements in electric swivel connector for portable appliances; and is particularly adapted, though not necessarily limited in its use with soldering irons, welding devices, curling irons, and the like, and one of the objects of the invention is to provide an improved connector of this character to prevent twisting or kinking of the conductor wire or cable, while permitting free use and turning of the appliance with respect to the cable, and providing an uninterrupted flow of electricity through the conductor wires or cable.

A further object is to provide an improved connector of this character, which will be encased within the handle of the appliance with which it is used, and, at the same time, will be of a simple and durable construction, and efficient and effective in operation.

To the attainment of these ends, and the accomplishment of other new and useful objects as will appear, the invention consists in the features of novelty in substantially the construction, combination and arrangement of the several parts, hereinafter more fully described and claimed, and shown in the accompanying drawings illustrating the invention, in which:

Figure 1 is an elevational view of a tool embodying this invention;

Figure 2 is a view of the parts separated;

Figure 3 is a longitudinal sectional view of the tool and swivel connection on an enlarged scale.

Figure 4 is an elevational view of one part of the connection.

Figure 5 is an elevation of the two connecting members removed from the tool.

Figure 6 is a sectional view of the contact members.

Figure 7 is a view taken on line 7—7 Figure 4.

In the accompanying drawings this improved connector is shown in connection with a soldering iron 10, in which there is the usual heating element (not shown), and having a handle formed of two separable sections 11, 12, fastened together against separation, in any desired or suitable manner, such as by means of screws 13, engaging telescoping portions of the sections.

Within the section 11 is arranged a plug 14 of insulating material removably secured in position against rotation with respect to the handle section, and preferably, by a screw 15. Arranged

2

within the plug are a pair of spring pressed contact members 16, 17, which are normally projected beyond the end of the plug. The plug is constructed of insulating material, and secured thereto, out of electrical connection with each other, are electrical contacts 18—19. One of these contacts, such as the contact 18, with the spring pressed contacts 16—17, has connected thereto a conductor cord or wire 20, constituting one side of an electric circuit to the implement 10, and the other contact 19 has connected to it a wire or conductor 21, constituting the other side of the circuit to the implement.

A separate contact member 22 is also mounted in the plug 14, and is spring pressed, so that one end thereof will be normally projected beyond the end of the plug. This contact 22 is preferably of a length to project beyond the ends of the contacts 16 and 17, for a purpose to be later described.

20 The contact 22 is electrically connected to the contact 19, to which the conductor 21 is connected, so as to complete the circuit through the conductors 20—21, when the parts are assembled in a manner to be set forth.

25 Within the section 12 of the tool handle, there is arranged a block of insulating material 23, secured in position, against rotation with respect to the handle, and by means of a screw 24, and rotatably mounted in said block is a tubular member 25 having a circumferential flange 26 intermediate its ends, and the flange is of a diameter

30 to fit within the handle section 10. A sleeve 27 may be provided in the block 23, if desired, to encompass the tubular member 25, to form a bearing 35 for the tubular member, a flange 28 being provided on the member to abut the lower face of the block. This flange 28 is disposed in proximity to, but spaced from the adjacent face of the flange 26, to form a race way for ball bearings 29. If desired, a washer 30 may be disposed between the balls 29 and the flange 28, to form a bearing for the balls, and the washer 30 is loose upon the tubular member 25.

35 The end of the tubular member 25 preferably terminates in an insulating block or member 31, and the block is preferably cut away, as at 32, to provide for contact terminals 33, 34, to which the ends of the conductor wires 35, 36 are respectively connected. These terminals 33, 34 are preferably supported by another insulating block or mem-

40 ber 37, which is secured to the handle section 10. The conductors 35, 36 are connected to the terminals 33, 34, and the conductors 20, 21 are connected to the terminals 18, 19, respectively, so that the conductors 20, 21, 35, 36 are connected in series to complete the circuit.

ber 37, which is fixed with respect to the block 31.

A contact plate 38 is secured to the block 37, and connected thereto and extending through this block is the terminal 33. The plate 38 is provided with an opening 39, which registers with an opening 40 in the block 31, and in alignment with the opening 40 is a portion of the contact terminal 34, to which latter the conductor wire 36 is electrically connected. When these parts are thus assembled, the elements 25, 31, 37, 38, and the contacts 33 and 34 will be fixed with respect to each other, and as the conductors 35 and 36 are contained within the cable 41, which is secured in any suitable manner to the rotatable tubular member 25, such as by means of a fastening device 42, it will be seen that a free rotation of these parts will be obtained with relation to the handle section 12, and bearing block 23 and the plug 14. The result will be that the operator may freely manipulate or turn the implement without twisting or kinking the conductor wires 35, 36. The contact 22, being longer than the contacts 16 and 17, will project therebeyond so as to enter the opening 39 in the member 38, to engage a portion of the terminal 34.

It will therefore be manifest that when the parts are thus assembled, the current will flow through the conductor 36, to the terminal 34, thence through contact 22, contact 19, conductor 21, through tool 10, conductor 20, contacts 18, contacts 16 and 17, conductor plate 38, terminal 33, and conductor 35, causing the tool to be heated. By the use of the ball bearing 29, and by reason of the contacts 16 and 17 engaging and moving over the contact plate 38, they will permit of a rotation of the plate 38, while the end of the contact 22, which engages the end of the terminal 34, will rotate with respect thereto, and thereby maintain electrical connection, without interrupting the circuit, at the same time maintaining the conductors 35, 36 and the cable 41 against kinking or twisting.

The point of connection of the cable 41 with the member 25, is preferably disposed within a recess 12a in the end of the handle 12, so as to protect the same.

While the preferred form of the invention is herein shown and described, it is to be understood that various changes may be made in the details of construction and in the combination and arrangement of the several parts, within the scope of the claims, without departing from the spirit of this invention.

What is claimed as new is:

1. A swivel connector for electric cables and the like, embodying a tubular sectional body, a member secured rigidly to one section of the body, spring pressed contacts passing through said member, a second member secured in the other body section, and spaced from the first said member, a rotatable contact bearing member in one of the sections and disposed between the said members, a conductor element passing through the said second member said rotatable member co-operating with the said second member to form a ball race way therebetween, balls in said race way, a cable secured to the said rotatable contact bearing member, and contact terminals connected with said cable, one of the last said terminals embodying an extended surface adapted to be engaged by certain of the spring pressed contacts, another of said spring pressed contacts passing through said surface and out of electrical connection therewith and adapted to engage a contact connected to the

cable, said spring pressed contacts adapted to be moved over the respective co-operating contacts when a said section is rotated with respect to the cable, the parts in the respective body members being removable as assembled units from the respective body members when the latter are separated.

2. A swivel connector for electric cables and the like, embodying two substantially cylindrical body sections connected in axial alignment, a bearing member in one of the sections and fixed with respect thereto, a sectional tubular member passing through and beyond said bearing, a flange on the end of said tubular member co-operating with the end of said bearing member to form a ball race way therebetween, balls in said race way, a rotatable insulating member fixedly connected with said tubular member beyond said race way, a contact plate carried by said insulating member, to which plate one end of a conductor is electrically connected, a second contact member carried by said rotatable insulating member, out of electrical connection with said plate, an insulating member carried by the other section, spring pressed terminals carried by the last said member, and conductors connected to the spring pressed terminals, certain of said terminals passing through said plate, out of electrical contact therewith and contacting the said second contact member, whereby the engaging contact member may be relatively rotated, all of the parts contained in each body section being removable as assembled units from the respective body members when the latter are separated.

3. A swivel connection of a character described, embodying a sectional tubular housing, a bearing member and a contact carrying member secured within the respective housing sections, against rotation with respect thereto and spaced from each other in a direction lengthwise of the housing, conductor members electrically connected with the said contacts, a rotatable contact carrying member disposed in one of the housing sections and in the space between said bearing member and the first said contact carrying member, and conductors electrically connected with the contacts on said rotatable member, the last said conductors passing through the said bearing member, the parts of the connection in the respective housing section being removable therefrom as separate and assembled units, when the housing sections are separated.

4. A swivel connection of the character described, embodying a sectional housing, a bearing member and a contact carrying member secured within the respective housing sections against rotation with respect thereto and spaced from each other in a direction lengthwise of the housing, conductor members electrically connected with the said contacts, a rotatable contact carrying member disposed in the space between said bearing member and the first said contact carrying member and within one of the housing sections, and conductors electrically connected with the contacts on said rotatable member, the last said conductors passing through the said bearing member, the said housing being of sectional construction, the said bearing member being secured in one of the housing sections and the first said contact carrying member being secured in another of the housing sections, the 75 parts of the connection in each housing section

being removable therefrom as assembled units, when the housing sections are separated.

5. A swivel connection for electric cables, embodying a casing comprising two sections, one end of one of the sections being reduced and telescoping into the other section, an insulation member secured in the end of one of the sections against rotation with respect thereto, spring pressed contacts carried by the said insulation member and projecting beyond the end thereof, an insulation member secured in the other section, spaced from said telescoping end and the first said insulation member and secured against rotation with respect to the section, a sleeve rotatably mounted in, and extending through the last said insulation member, a flange on and secured to said sleeve within the space between the insulation members and spaced from the end of the sleeve, ball bearings between the said flange and the second said insulation member, an insulation contact supporting member secured to said sleeve within the space between the first two said insulation members, contact terminals carried by the said insulation contact supporting member, and conductors passing through the sleeve and secured to the last said contact members, one of the last said contact members having an opening through which one of the first said spring pressed contacts passes, and the other of the first said contacts engaging the other contact member on the rotatable insulation member.

6. A swivel connection for electric cables, embodying a casing comprising two sections, one end of one of the sections being reduced and telescoping into the other section, an insulation member secured in the end of one of the sections against rotation with respect thereto, spring pressed contacts carried by the said insulation member and projecting beyond the end thereof, an insulation member secured in the other section, spaced from said telescoping end and the first said insulation member and secured against rotation with respect to the section, a sleeve rotatably mounted in, and extending through the last said insulation member, a flange on and secured to said sleeve within the space between the insulation members and spaced from the end of the sleeve, ball bearings between the said flange and the second said insulation member, an insulation contact supporting member secured to said sleeve within the space between the first two said insulation members, contact terminals carried by the said insulation contact supporting member, conductors passing through the sleeve and secured to the last said contact members, one of the last said contact members having an opening through which one of the first said spring pressed contacts passes, and the other of the first said contacts engaging the other contact member on the rotatable insulation member, a cable within which said conductors are located, and means connecting the end of the cable to said sleeve, within and spaced from the end of the casing sections.

7. A swivel connection for electric cables, embodying a casing comprising two sections, one end of one of the sections being reduced and telescoping into the other section, an insulation member secured in the end of one of the sections against rotation with respect thereto, spring pressed contacts carried by the said insulation member and projecting beyond the end thereof, an insulation member secured in the other section, spaced from said telescoping end and the

first said insulation member and secured against rotation with respect to the section, a sleeve rotatably mounted in, and extending through the last said insulation member, a flange on and secured to said sleeve within the space between the insulation members and spaced from the end of the sleeve, ball bearings between the said flange and the second said insulation member, a hollow insulation contact supporting member secured to said sleeve within the space between the first two said insulation members, contact terminals carried by the said insulation contact supporting member, and conductors passing through the sleeve into the hollow insulation member, and secured to the last said contact members, one of the last said contact members having an opening through which one of the first said spring pressed contacts passes, and the other of the first said contacts engaging the other contact member on the rotatable insulation member.

8. A swivel connection for electric cables, embodying a casing comprising two sections, one end of one of the sections being reduced and telescoping into the other section, an insulation member secured in the end of one of the sections against rotation with respect thereto, spring pressed contacts carried by the said insulation member and projecting beyond the end thereof, an insulation member secured in the other section, spaced from said telescoping end and the first said insulation member and secured against rotation with respect to the section, a sleeve rotatably mounted in, and extending through the last said insulation member, a flange on and secured to said sleeve within the space between the insulation members and spaced from the end of the sleeve, ball bearings between the said flange and the second said insulation member, an insulation contact supporting member secured to said sleeve within the space between the first two said insulation members, contact terminals carried by the said insulation contact supporting member, and conductors passing through the sleeve and secured to the last said contact members, one of the last said contact members having an opening through which one of the first said spring pressed contacts passes, and the other of the first said contacts engaging the other contact member on the rotatable insulation member.

9. A swivel connection for electric cables, embodying a casing comprising two sections, one end of one of the sections being reduced and telescoping into the other section, an insulation member secured in the end of one of the sections against rotation with respect thereto, spring pressed contacts carried by the said insulation member and projecting beyond the end thereof, an insulation member secured in the other section, spaced from said telescoping end and the first said insulation member and secured against rotation with respect to the section, a sleeve rotatably mounted in, and extending through the last said insulation member, a flange on and secured to said sleeve within the space between the insulation members and spaced from the end of the sleeve, ball bearings between the said flange and the second said insulation member, an insulation contact supporting member secured to said sleeve within the space between the first two said insulation members, contact terminals car-

ried by the said insulation contact supporting member, and conductors passing through the sleeve and secured to the last said contact members, one of the last said contact members having an opening through which one of the first said spring pressed contacts passes, and the other of the first said contacts engaging the other contact member on the rotatable insulation member, the rotatable insulation contact carrying member, the contacts carried thereby, and the said sleeve and bearing being removable as an assembled unit, from the respective casing section.
